CLAIM

The ornamental design for a telephone set, as shown and described.

DESCRIPTION

FIG. 1 is a front elevational view of a telephone set showing my new design;

FIG. 2 is a side elevational view thereof, taken from the right with respect to FIG. 1;

FIG. 3 is a top plan view thereof;

FIG. 4 is a side elevational view of the side opposite to that shown in FIG. 2;

FIG. 5 is a rear elevational view thereof; and,

FIG. 6 is a bottom plan view thereof.
